UNITED STATES PATENT OFFICE.

MICHAEL W. McCARDLE, OF CHICAGO, ILLINOIS.

PLUG FOR ELECTRIC-CIRCUIT CONNECTIONS.

Application filed April 16, 1925. Serial No. 23,545.

The purpose of this invention is to provide an improved construction of a detachable plug for electric circuit connection of the type commonly employed for connecting 5 to electric irons and other portable electric devices. It consists in the elements and features of construction shown and described and as indicated in the claims.

In the drawings:—

10 Figure 1 is a side elevation of a plug embodying this invention in one of the two forms to be described.

Figure 2 is a section at the line 2—2 on Figure 1, being substantially a top plan 15 view of the device shown in said Figure 1.

Figure 3 is a side elevation of the housing with the securing clips or clasps removed and without the inleading circuit wires.

Figure 4 is an elevation of the inner face 20 of one of the housing members with the inleading circuit wires and terminals in place therein.

Figure 5 is a perspective view of one of the clasps by which the housing members 25 are held together.

Figure 6 is a section at the line 6—6 on Figure 1.

Figure 7 is a view similar to Figure 1 showing a different form of the device.

30 Figure 8 is a side elevation of one member of the housing of the form shown in Figure 7 stripped of the securing clasps and inleading wires.

Figure 9 is a section at the line 9—9 on 35 Figure 7.

Figure 10 is a perspective view of one of the clasps for the forms shown in Figures 7 and 8.

40 Figure 11 is an elevation of the clasp shown in Figure 10 in its form before having been folded into the fork or clasp formation.

Figure 12 is an elevation of the inner face 45 of one of the housing members with the inleading circuit wires and terminals in place therein.

The form of the device shown in Figures 1 to 6 inclusive will first be described. The device comprises a housing consisting of two 50 members of identical formation made of insulating material, mated face to face, having in their meeting faces recesses for accommodating the inleading wires and terminals thereof, and having on their outer faces recesses for seating the securing devices which 55 are in the form of forked clasps as herein-

after described. The form of the housing members, 10, 10, may be understood most clearly from Figures 3 and 4. In Figure 3 there may be seen the exterior recesses for 60 accommodating the forked clasp hereinafter described, said recesses comprising the longitudinal portion 10^b, for accommodating the fork arms of the clasp, the top or cross-over portion, 10^c, for accommodating the nexus 65 of the clasp, and the portion, 10^a, at the lower end for accommodating the transverse fork bars of the clasp. In Figure 4 may be seen the interior recess for accommodating the inleading circuit wires and terminals, 70 said recess being continuous and indicated throughout by the reference character, 10^a, applied at several parts of that recess to indicate its continuity. The specific purpose of the invention is to dispense with screws 75 or the like for attaching or clamping together the housing members for enclosing the inleading circuit wires and terminals, and the clasps, for that purpose, are of fork formation, two clasps being applied one over 80 and the clasps, for that purpose, are of fork arms extending down at opposite sides in the identical exterior longitudinal recesses, 10^b, of the two housing members and having transverse fork arms at the lower ends of the 85 longitudinal arms for seating in the recesses, 10^a, of the housing members respectively. These clasps, indicated each as to its entirety by the reference numeral, 11, comprise therefore each two longitudinal fork arms, 90 11^a, a nexus, 11^b, connecting them for lodgment in the recess, 10^b, at the shoulder of the housing and a transverse fork bar, 11^c, at the lower end of each of the longitudinal fork bars, 11^a, these transverse bars not being 95 continuous with each other but severed substantially at the parting plane of the housing members as seen at 11^d, and being preferably inwardly flanged at their lower edges as seen at 11^e, for hooking over the lower 100 ends of the housing members. It may be understood that the manner of assembling the device will be to first lodge the inleading circuit wires with their terminals in one member of the housing as seen in Figure 4, 105 then apply the other housing member to the first, mating the two members line for line, then introducing over the shoulders of the assembled housing, the clasp members one by one, sliding them down until the longitudinal fork arms and the transverse fork arms at the lower ends snap into their re- 110

2

spective seats formed by the surface recesses in the housing members. It will be understood that reliance is placed upon the resiliency of the metal of which the fork members are composed to adapt them thus to snap into and be held securely in their seats, and it will be understood that for this quality or function the nexus which lodges in the shoulder recesses of the housing member should be relatively quite stiff. To obtain the desirable stiffness the clasps may be constructed as seen most clearly in Figure 5, each clasp being made of two pieces folded at the upper ends for forming the nexus, the folded ends indicated at 11^l in Figure 5 being lapped upon each other and clamped together by screws, 11^g, taking through the lapped ends and engaging the clamping bar, 11^k, at the inner side, whereby the nexus is made to consist of substantially three thicknesses of metal. Advantage may be taken of this two piece construction of the clasp to avoid reliance upon the resiliency of the metal for applying the clasp, the screw 11^g being withdrawn and the two members released from clamping sufficiently so that they may be spread to permit the clasp to be applied and its members introduced into their proper seats without materially springing the metal, the screws being then tightened and thereby drawing the members together for snug seating throughout.

The form shown in Figures 7, 8, 9, 10 and 11 differs from that shown in the preceding figures chiefly in that instead of having the longitudinal fork arms extended up and over the top shoulder of the housing, they are deflected below the shoulder so that the nexus crosses the lateral or vertical side edge instead of the top or shoulder. This difference may be most clearly understood by comparing the perspective views of the clasp members in the two forms, namely, Figures 5 and 10. Describing this second form in detail—the housing members, 20, 20, have their interior faces provided with a recess, 20^a, for seating the inleading wires and terminals and their outer surfaces provided with the recess comprising the longitudinally extending portion, 20^b, deflected below the shoulder at 20^c leading to the cross-over recess, 20^d, the longitudinal recess, 20^b, being continuous from its lower end with the transverse recess, 20^e, which, as in the form of the earlier figures, extends around the lateral edge of the housing as seen at 20^f. The clasp member for this form of housing comprises the longitudinal fork arm, 21^a, deflected outwardly at 21^b, and extending thence transversely in the portion, 21^c, to the nexus, 21^d, this description applying to both sides of the clasp, or both arms of the fork. This formation having the transverse deflection of the longitudinal arm to reach the nexus, 21^d, and the nexus being across the vertical edge

instead of across the top shoulder of the device, affords opportunity for providing a longitudinal bar at the edge of the housing lapping the meeting plane of the housing members as shown at 21^e, this arm extending down between the severed or parted ends of the transverse arm, 21^k, as seen in Fig. 11, said transverse arm having an inturned flange, 21^h, and the end of the bar, 21^g, being bent inward at the lower end as seen at 21ⁱ, to supplement this flange by similar engagement with the lower end of the housing.

I claim:—

1. An electric circuit connection plug comprising for holding inleading circuit terminals and contacts, mated housing members of insulating material adapted for enclosing between them and separating from each other the circuit terminals, and forked clasps adapted to be applied exteriorly to said housing members astride the meeting plane of said members, each fork arm comprising a part which extends longitudinally of the housing, and a part extending transversely of the same, the housing members having surface recesses correspondingly arranged extending longitudinally and transversely for seating said forked arm, whereby the clasps stop the housing members relatively to each other both longitudinally and transversely.

2. An electric circuit connection plug comprising for holding inleading circuit terminals and contacts, mated housing members of insulating material adapted for enclosing between them and separating from each other the circuit terminals, two independent clasps adapted to be applied each for striding one longitudinal edge of the housing, the housing members having each in the outwardly facing lateral surfaces at opposite sides of the middle longitudinal line thereof recessed seats extending longitudinally of the housing for receiving correspondingly arranged bars of the respective clasps, each fork arm of each clasp comprising a bar positioned for seating in the corresponding longitudinal recess of the housing member at the striding position of the clasp.

3. An electric circuit connection plug comprising for holding inleading circuit terminals and contacts, mated housing members of insulating material adapted for enclosing between them and separating from each other the circuit terminals, and forked clasps adapted to be applied exteriorly to said housing members astride the meeting plane of the housing members each comprising a pair of fork branches extending longitudinally, and a pair of fork branches extending transversely of the housing, the transversely extending fork branches being toward the end opposite that at which the

circuit wires enter the housing, and being parted at a plane intermediate said fork arms, whereby the connection of the two transversely extending fork arms is formed by the connection between the two longitudinally extending arms.

4. An electric circuit connection plug comprising for holding inleading circuit terminals and contacts, mated housing members of insulating material adapted for enclosing between them and separating from each other the circuit terminals, and forked clasps adapted to be applied exteriorly to said housing members astride the meeting plane of the latter, each clasp having longitudinally extending and transversely extending fork arms, the transversely extending arms being carried respectively at the

ends of the longitudinally extending arms and being severed from each other at a plane intermediate said arms, whereby the connection between the longitudinal fork arms constitutes the sole connection between the transverse fork arms, the longitudinally extending arms being rigidly and separably secured together, and an exteriorly accessible and operable screw for securing the arms together; whereby the fork may be parted and the two parts separately and directly lodged in and withdrawn from the surface recesses in the housing members respectively.

In testimony whereof, I have hereunto set my hand at Chicago, Illinois, this 26th day of February, 1925.

MICHAEL W. McARDLE.
